UNITED STATES PATENT OFFICE

CHARLES W. TIMMONS, OF LAPEL, INDIANA

ALARM SWITCH FOR AUTOMOBILES, SAFES, AND THE LIKE

Application filed January 9, 1928. Serial No. 245,504.

This invention relates to alarms or signals for use in conjunction with combination or permutation locks and which can be used to advantage on the ignition system of automobiles, safe doors, and the like.

One of the primary objects of this invention is to provide novel means for operating a signal or alarm when persons unfamiliar with the combination of the lock or the characteristics thereof endeavor to operate the lock or force the dial of the lock inward or by otherwise tampering therewith.

Another important feature of the invention is the provision of an alarm circuit incorporated with the combination lock, and means for closing said circuit upon the tampering with the lock by unauthorized persons.

A further object of the invention is the provision of a combination lock having a rod rotatably carried with the dial of the lock and slidably mounted therein, the rod carrying novel means for bridging contacts for closing an alarm or signal circuit upon unauthorized movement of the dial, means being provided whereby persons familiar with the lock are enabled to move the rod to a predetermined position whereby closing of the alarm or signal circuit will be prevented during the ordinary working of the combination lock.

A further object of the invention is to provide novel means operated by the bolt of the lock for closing a circuit after the correct operation of the lock, the circuit being, for instance, the ignition circuit of an automobile.

A still further object of the invention is to provide a burglar alarm or signal for permutation lock of the above character, which will be durable and efficient in use, one which will be simple and easy to manufacture and one which can be incorporated with the ignition system of an automobile or a safe door at a small cost.

With these and other objects in view, the invention consists in the novel construction, arrangement and formation of parts, as will be hereinafter more specifically described, claimed, and illustrated in the accompanying drawings, in which drawings:

Figure 1 is a side elevation of the improved device showing the same incorporated with the instrument board of an automobile for use in conjunction with the ignition circuit thereof,

55

Figure 2 is a horizontal section through the instrument board of an automobile showing the improved device incorporated therewith, the device being shown in top plan,

60

Figure 3 is a transverse section through the device taken on the line 3—3 of Figure 2 looking in the direction of the arrows, illustrating a part of the alarm circuit-closing apparatus,

65

Figure 4 is a transverse section through the apparatus taken on the line 4—4 of Figure 2 looking in the direction of the arrows, illustrating the means for connecting the bridge strip for the automobile ignition circuit with the bolt of a combination lock,

70

Figure 5 is a transverse section through the apparatus taken on the line 5—5 of Figure 2 looking in the direction of the arrows, illustrating one method of incorporating the alarm signal buzzer in place,

75

Figure 6 is a fragmentary longitudinal section through the complete apparatus showing the same incorporated with the instrument board of an automobile,

Figure 7 is a detailed perspective view of one segment of the circuit-closing guard,

80

Figure 8 is a detailed perspective view of the bridge strip for the alarm circuit and its operating rod,

85

Figure 9 is a fragmentary detailed perspective view illustrating the bridge strip for the ignition circuit carried by the bolt of the combination lock,

Figure 10 is a diagrammatic view illustrating the various circuits when the device is used in conjunction with the ignition circuit of an automobile, and

90

Figure 11 is a diagrammatic view illustrating the various circuits when the device is incorporated with the door of a bank safe or the like.

95

Referring to the drawings in detail, wherein similar reference characters designate corresponding parts throughout the several views, the letter A generally indicates a form

100

of the improved apparatus when the same is incorporated with an automobile.

A fragment of the instrument board 15 of an automobile has only been shown, as the invention resides in the novel apparatus A.

In the form A of the invention, the combination lock indicated by the reference character 20 is secured in any desired way to the instrument board 15 with the casing 21 of the lock disposed on the inside of the instrument board and the dial 22 on the exterior of the said board. The casing 21 is of the usual construction and will not be described in detail but it is to be noted that the bolt 23 of the lock projects upwardly from the casing as clearly shown in Figures 6 and 9 of the drawings for a purpose, which will be later described.

The dial and knob 24 thereof are provided at their axial center with an opening which is polygonal shaped in cross-section for slidably receiving a combination rod 25 which forms an essential part of the invention. This rod is of the same shape in cross section as the opening in the knob 24 and dial 22, so that the rod will be rotated with the dial. The dial 22 is graduated in the usual manner as at 26 for a purpose which will be later described and the face plate is provided with an indicating line 27 to facilitate the manipulation of the dial and the working of the combination of the lock. The extreme outer end of the rod 25 is provided with an operating thumb piece 28 and one face of the rod is provided with suitable numbered graduations 29 for a purpose which will be later described.

The device A also includes a supporting frame 30 which is of a substantially U-shape in plan and the forward terminals of the arms of the frame are provided with right angularly extending attaching feet 31 which are bolted or otherwise secured to the inner face of the instrument board 15.

Arranged intermediate the ends of the frame 30 and disposed transversely thereof is a novel guard and contact device 32 which consists of semi-annular sections 33 and 34 respectively. These sections 33 and 34 are formed of electric conducting material and are secured in any desired way to the arms of the frame 30 with their adjacent ends slightly spaced, defining ways 35 diametrically arranged, for a purpose which will be later described. As clearly shown in Figure 7 of the drawings, the sections 33 and 34 have their adjacent ends provided with inwardly directed lips 36 which form the sides of the ways 35.

Extending inwardly from the sections 33 and 34 are relatively long contact strips 37 and a strip is carried by each section and the two strips are diametrically disposed and are preferably arranged adjacent to but spaced from the guide ways 35. Projecting

forwardly from the sections 33 and 34 are relatively short contact and stop strips 38 and these strips are also diametrically disposed and arranged at opposite points, preferably at quarters, to the contact and stop strips 37.

Relatively long contact pins 39 and 40 are secured to the inner face of the instrument board 15 and these strips are preferably insulated therefrom in any desired way, such as by the use of insulating gaskets or the like. These pins terminate adjacent to but spaced from relatively short contact strips 38 and thus a way is defined between the contact pins 39 and 40 and the relatively short contact strips 38.

Extending transversely across the frame 30 is a brace strip 41 which is secured in any desired way to the arms of the frame in spaced relation to the connecting body portion thereof and the relatively long contact and stop strips 37. Rigidly connected to the brace strip 41 and projecting forwardly therefrom are a pair of spaced contact tongues 42 formed of electric conducting material and these tongues also end short of the contact and stop strips 37 and are disposed at the axial center of the entire device, that is, in axial alignment with the center of the dial 22 and the sliding rod 25. If desired, the various contact tongues, strips and the like can be insulated from the frame 30 and brace strip 41 or, as shown, the frame and the brace strip can be formed from insulating material so that the current is normally broken between said tongues, strips and the like.

The connecting body portion of the frame preferably supports the signalling device which, as shown, can be in the nature of a buzzer or bell 43.

In accordance with this invention, lead and return wires 44 and 45 are connected to a suitable source of electrical energy, such as a battery 46' which can be considered as the usual storage battery of the motor vehicle. The lead wire 44 is electrically connected with one contact tongue 42 while the return wire is connected to one terminal of the buzzer 43, as clearly shown in the drawings. The other binding post of the buzzer 43 is connected by means of a wire 46 with the other contact tongue 42, as clearly shown.

Electrically connected with the tongues 42 are electric wires 47 and 48 which are electrically connected respectively with the sections 33 and 34 of the circuit-closing apparatus and to the contact pins 39 and 40.

In accordance with this invention, a bridge head 49 formed of electric conducting material is carried by the inner end of the rod 25 and this head can be insulated from the rod 25. This head is of a sufficient size to bridge the contact tongues 42 when the rod is pushed inwardly beyond a predetermined point, as will be later brought out. The inner end of

the head carries a bridge strip 50 which extends diametrically through the head and the rod 25 and is insulated therefrom by the use of a sleeve 51 formed of insulating material. This bridge strip 50 is relatively narrow, so that the same can slide through the ways 35 without contacting with the members 33 or 34 and the lips 36 thereof, when properly actuated.

10 The combination lock 20 is utilized for controlling the ignition circuit 55 of the internal combustion engine (not shown) of the automobile and when this lock is actuated correctly the circuit through the ignition is closed. As shown, wires 56 and 57 lead from the ignition circuit and are electrically connected with contact jaws 58 and 59 respectively which are carried by the arms of the frame 30. The bolt 23 of the lock has connected directly therewith a block of insulation 60 which supports the transversely extending bridge rod 61 which is adapted to engage the jaws 58 and 59 and thus bridge the circuit when the lock is operated.

25 In operation of the improved device, the bolt 23 is normally in a raised position with the bridge rod 61 above the jaws 58 and 59 with the rod 25 disposed in its innermost position and the bridge strip between the relatively long contact strips 37. It can be seen that when unauthorized persons endeavor to operate the lock that, upon the turning of the dial 22, the rod 25 will be rotated therewith and the bridge strip 50 will come in contact with the contact and stop strips 37 which will close the alarm circuit through the buzzer 43 giving an effective alarm. In this instance, the current will flow from the battery 46 to the wire 44, wire 47, section 33, one contact and stop strip 37 to the bridge strip 50, to the other contact and stop strip 37 through section 34, wire 48, wire 46, through the buzzer, through the wire 45 and back to the battery 46'. If the rod or entire dial is forced inward, the contact bridge head 49 will engage the contact tongues 42 and thus close the circuit through these contacts and again sounding the alarm. If the rod 25 is pulled forwardly, the same will engage the sections 33 and 34 and close the circuit between and through the buzzer 43, as previously described and thus the alarm will be sounded in this instance. At this point, it might be stated that the inner edges of the sections 33 and 34 can be provided with suitable notches or stops if so desired so as to prevent the easy locating of the ways 35.

30 Thus, if, by chance, the ways 35 are located by the person endeavoring to operate the lock and the dial is then turned, the bridge strip will engage the short contact and stop strip 38 which will again close the circuit. If the rod is pulled further out, the contact pins 39 and 40 will be bridged and

the alarm will again be sounded. Thus, in order to operate the combination lock safely, the bridge strip 50 must be disposed between the short contact and stop strips 38 and the contact pins 39 and 40 and the finding of this position without sounding the alarm, by unauthorized persons, is, of course, exceedingly remote.

To operate the lock by a person who is familiar with the combination, the dial 22 is first turned to a predetermined position, say with the graduation 30 aligning with the indicating mark 27 which will align the bridge strip 50 with the ways 35 after which the rod is pulled forwardly through the ways 30 and is stopped at a predetermined point at one of the graduations, say 12, which will align the bridge strip with the ways between the contact pins 39 and 40 and the short bridge strips 38. At this time, the combination of the lock can be worked in the usual way and the alarm will not be sounded.

In Figure 11, I have illustrated the novel alarm signal incorporated with the lock of a safe and the device is of identically the same construction as described, the only difference being the elimination of the contact jaws and bridge strips of the ignition circuit, the lock bolt being utilized in this instance for locking the safe door.

In this form of the invention, it is also preferred to provide means for operating the alarm in case heat is applied to the door, such as an acetylene torch or the like for burning an opening therein. In this instance, suitable plates of metal 70 and 71 are arranged adjacent to the door and these plates have the properties of expanding under the influence of heat and are adapted to contact when the temperature of the door arises above a predetermined degree. These plates have connected therewith respectively wires 72 and 73 which are connected with the wires 47 and 48 which leave the sections 33 and 34 of the circuit device 32.

It is obvious that to operate this lock of the safe, it is also necessary to dispose the rod 25 in a predetermined way before the lock can be operated without sounding the alarm.

Changes in details may be made without departing from the spirit or the scope of this invention but:

What I claim as new is:

1. In an electric alarm circuit, a circuit controlling device comprising a rotatable dial, a rod slidably carried by the dial and rotatable therewith, a pair of contact members arranged in rear of the rod and adapted to be engaged by the rod upon inward movement thereof, a pair of semi-circular contact members arranged forwardly of the first contact members, contact strips carried by the semi-annular contact members, a bridge strip carried by the rod and normally disposed in the path of said contact strips, said semi-

annular members having their terminals spaced a sufficient distance to permit the passage of said bridge strip therethrough without contact therewith, when the dial is in a predetermined position, contact pins arranged forwardly of the semi-annular contact members in a predetermined spaced relation relative thereto.

2. In an electric alarm circuit, a circuit controlling device comprising a rotatable dial, a rod slidably carried by the dial and rotatable therewith, a pair of contact members disposed in the circuit and arranged in rear of the rod and adapted to be engaged by the rod upon inward movement thereof, a pair of semi-annular contact members arranged forwardly of the first contact members, contact strips carried by said semi-annular contact members, and a bridge strip carried by the rod and normally disposed in the path of the said contact strips, said semi-annular members having their terminals spaced a sufficient distance to permit the passage of said bridge strip therethrough without contact therewith when the dial is in a predetermined position.

In testimony whereof I affix my signature.
CHARLES W. TIMMONS.
